UNITED STATES PATENT OFFICE.

LOUIS ZIMSKIND, OF NEW YORK, N. Y.

DESIGN FOR A BEDSTEAD.

SPECIFICATION forming part of Design No. 20,458, dated January 6, 1891.

Application filed November 4, 1890. Serial No. 370,348. Term of patent 14 years.

To all whom it may concern:

Be it known that I, LOUIS ZIMSKIND, a citizen of the United States of America, residing at the city, county, and State of New York, 5 have invented a Design for a Metal Bedstead, of which the following is a full, clear, and exact description.

The principal feature of this design consists in the ornamental shape and configuration of 10 the head and foot guards of the bedstead, wherein the top is an arched prolongation of the legs and the middle portions of the legs have a twisted configuration.

The design for the bedstead is shown in the 15 accompanying drawing.

The top *a* of the head or foot guard is an

arch between the upper ends of the legs *b*, and the legs are ornamented by the twisted portions *c* near the middle, and vertical bars *d* and horizontal bar *e* compose portions of 20 the design of the guard.

I claim—

In the design for a metallic bedstead, the 25 design of the ornamental head or foot guard and legs, substantially as represented.

Signed by me this 3d day of November, 1890.

LOUIS ZIMSKIND.
